UNITED STATES PATENT OFFICE.

JOHN EVERETT CLARK, OF PROVIDENCE, RHODE ISLAND.

WINDSHIELD WIPER.

Application filed December 7, 1927. Serial No. 238,357.

This invention relates to an improved construction of wiper for windshields designed to remove snow and ice therefrom and has for its object to construct a wiper for this purpose which is provided with a liquid holding backing tube having a wiping strip of flexible material fixed along its length, the tube having a plurality of holes through which the ice affecting liquid is supplied to 5 the strip to be deposited on the surface of the windshield by a movement of the wiper.

A further object of the invention is the forming of this tubular member into a plurality of liquid holding compartments from 15 which the strip is supplied with the liquid contained in each for the purpose of obtaining a more even distribution of the liquid upon the strip and by the strip distributed upon the surface of the windshield with 20 which it comes in contact.

A still further object of the invention is the provision of a plurality of graduated holes thru the wall of the wiper, these holes decreasing in size toward the bottom of the 25 tube to more nearly equalize the flow of the liquid to the strip of wiping material.

With these and other objects in view, the invention consists of certain novel features of construction, as will be more fully 30 described, and particularly pointed out in the appended claims.

In the accompanying drawings:

Figure 1 is a perspective view illustrating my improved wiper as mounted to be operated automatically across a portion of the 35 face of the windshield.

Figure 2 is an enlarged sectional elevation showing the tube as divided into a plurality of liquid holding compartments each 40 communicating thru holes with the flexible wiping material.

Figure 3 is a view of the back of the tube.

Figure 4 is a section on line 4-4 of Figure 2 thru the tube showing a plurality of 45 different compartments.

Figure 5 is a section on line 5-5 of Figure 2.

Figure 6 is a section on line 6-6 of Figure 2.

Figure 7 is a perspective view of the arm 50 at the point where it is attached to the backing tube of the wiper.

It is found in practice particularly during the winter months that ice and snow 55 accumulate on the surface of a windshield to such an extent that it cannot be removed by

action of the ordinary wiper and materially interferes with the vision of the vehicle operator and my present invention is designed for the purpose of dissolving or removing 60 this ice and snow from the surface of a windshield and spreading upon the surface a material which will also prevent the further freezing of the moisture to this surface and to accomplish this in a simple and effective way, I have formed a tubular backing member arranged to carry a supply of liquid such as ether or alcohol or other suitable liquid and have arranged for this liquid to be deposited upon the flexible wiper which I 70 preferably form of absorbent material, the same being arranged to be moved to cover a portion of the surface of the windshield to assist in preventing icy deposit and also remove any such deposit of snow and ice which 75 may have formed thereon. It is found that the forming of a tubular member of this character with a plurality of separate compartments materially assists in the more complete distribution of the liquid along the 80 contacting surface of the wiping material to produce the best results; and the following is a detailed description of the present embodiment of my invention and showing one means by which these advantageous results 85 may be accomplished.

With reference to the drawings 10 designates the backing tube which is of any suitable length, the interior of the tube being provided with a separating wall 11 having 90 a bottom portion 12 and another wall 13 having a bottom portion 14 providing upper, intermediate, and lower compartments in the tube.

This tubular member 10 is provided with 95 bendable side lips 15 along its rear edge between which a strip of absorbent material 16 such as felt or the like is positioned and these side walls are bent inward to grip the same and so hold this material against the 100 rear wall 17 of this backing member. The rear wall of the upper compartment 18 is provided with holes 19 which communicate with the corresponding portion of the felt wiper. The intermediate compartment 20 is provided with holes 21 communicating with its portion of the felt and the lower compartment 22 is provided with holes 23 communicating with its portion of the felt wiper. The holes 19 in the upper compartment being preferably larger than those in the intermediate compartment and holes 23

in the lower compartment being slightly smaller than those in the intermediate compartment, whereby there is a little greater proportion of the liquid in the upper portion 5 is permitted to flow to the wiping material as this liquid is designed to work downwardly by its gravity and also upward by capillary attraction, and these two oppositely acting influences serve to provide a 10 fairly even distribution along the length of the wiping material particularly as the wiper is oscillated back and forth the liquid is caused to run back and forth along the walls of the different compartments and 15 splash thru the openings especially when rapidly operated.

A cork or closure member 24 is placed in the upper end of the tube to close all of these tubes simultaneously so that they will not 20 communicate with each other.

The whole wiping device is suspended from the operating arm 25 which is connected at its lower end as at 26 to the fin 27 on the back of the wiper tube and is connected at its upper end as at 28 to the usual automatically operating device 29 which imparts movement thereto.

My improved wiper is very simple and practical in construction and effective in its 30 operation and by its use the cleaning liquid is evenly distributed along the length of the wiping material to remove the snow and ice from that portion of the windshield with which it comes in contact and when any portion 35 of the felt becomes dry and fails to effectively perform its cleaning operation this surface serves as a signal to the operator that the whole device needs refilling.

The foregoing description is directed

solely towards the construction illustrated, 40 but I desire it to be understood that I reserve the privilege of resorting to all the mechanical changes to which the device is susceptible, the invention being defined and limited only by the terms of the appended 45 claims.

I claim:—

1. A wiper for wind shields comprising a wiping strip of absorbent material to engage the windshield, a liquid holding backing 50 tube fixed along said strip of a length substantially the length of the strip, said tube having a set of graduated holes along its length decreasing in size toward the bottom thereof and communicating with and supplying said absorbent material with a liquid from the tube to be deposited upon the windshield by a movement of the wiper. 55

2. A wiper for windshields comprising a backing tube divided into a plurality of 60 liquid holding compartments, a wiping strip secured to said tube the wall of each compartment having a hole thru which the liquid is supplied to said strip to be deposited in the surface of the windshield with 65 which the strip contacts.

3. A wiper for windshield comprising a backing tube divided into a plurality of non-communicating liquid holding compartments, a closure member for said compartments, a wiper strip secured to said tube, each compartment having a hole thru which liquid from said compartments is supplied to different portions of said strip to be applied to the surface of the windshield along 75 the length of the wiper.

In testimony whereof I affix my signature.
JOHN EVERETT CLARK.
